UNITED STATES PATENT OFFICE

2,417,200

SWITCH

John H. Horman, Tuckahoe, N. Y., assignor, by
mesne assignments, to Allied Control Company,
Inc., New York, N. Y., a corporation of New
York

Application August 10, 1944, Serial No. 548,839

6 Claims. (Cl. 200—6)

1

This invention relates to switches.

A certain type of switch consists of an oscillatable bridging member which is movable between two positions in one of which the ends of the bridging member engage one pair of contacts and in the other of which the ends of the bridging member engage a different pair of contacts. Such type switch is often embodied in a relay structure with the bridging member being carried by an oscillatable armature.

An object of this invention is a mounting for the bridging member of this type switch so that definite engagement of the bridging member ends with the contacts is assured.

In a switch embodying the invention, the bridging member is provided with an opening in which is received the end of an oscillatable shaft. A resilient member is fixed to said shaft and has its ends connected to the ends of the bridging member. The bridging member is provided with a pair of contacts at each end and a pair of stationary contacts is provided for engagement by each set of bridging member contacts. Oscillation of the shaft is effected by any suitable means such, for example, as the armature of a rotary magnet and rotary movement is transmitted from the shaft to the bridging member through the medium of the resilient member. The design is such that the shaft has a certain amount of overtravel so that when the shaft comes to rest the bridging member contacts are pressed into engagement with the stationary contacts under tension exerted by the resilient member.

Other objects, novel features and advantages of this invention will become apparent from the following specification and accompanying drawings, wherein:

Fig. 1 is a plan view of a rotary type relay equipped with a switch embodying the invention;

Fig. 2 is a side elevation thereof;

Fig. 3 is a section on the line 3—3 of Fig. 2;

Fig. 4 is a side elevation of a modification;

Fig. 5 is a section on the line 5—5 of Fig. 4, and

Fig. 6 is a section on the line 6—6 of Fig. 4.

The relay embodies a coil and armature arrangement not specifically shown and this particular structure is not part of this invention. The armature is supported by an oscillatable shaft 10 on which is mounted a contact bridging member 11. The shaft 10 has a cylindrical axial recess 12 with opposed radial slots 13 leading therefrom to the exterior of the shaft. Two

2

thin resilient plates 14 and 15 fit into the slots 13 and have semi-cylindrical offset portions 16 and 17 fitting the cylindrical recess 12 and serving to prevent radial movement of the plates. A second pair of heavier but resilient metal plates 18 and 19 have semi-cylindrical offsets 20 and 21 surrounding the shaft 10 with substantial clearance between the shaft and the plates. The plates 14 and 15, 18 and 19 are interconnected 10 at their ends and carry contacts 22 and 23. Preferably, the plates 14 and 15 are of slightly greater width centrally than the plates 18 and 19. The central portions of the plates 14 and 15 rest on a shoulder 24 on the shaft 10 and are engaged by the nut 25 on the shaft whereby the bridging member 11 is supported by the shaft.

A pair of stationary contacts 26 are provided for alternate engagement by the contacts 22 and a similar pair of stationary contacts 27 are 20 provided for alternate engagement by the contacts 23. The shaft 11 is rotated clockwise electromagnetically to establish engagement between the bridging member 11 and one combination of stationary contacts 26 and 27 and is rotated 25 counterclockwise by a spring 28 to establish engagement between the member 11 and the remaining set of contacts 26 and 27. A slight overtravel of the shaft 10 beyond that necessary to establish engagement between the movable and 30 stationary contacts is permitted by the resiliency of the plates 14 and 15 as well as by the clearance between the shaft 12 and the portions 20 and 21 of the plates 18 and 19.

In the modification of Figs. 4, 5 and 6, the shaft 10 is provided with a slot 29 in which is received a length of resilient wire 30 bent into the shape shown in Fig. 6. From one end of the slot 29, the wire 30 overlies the periphery of the shaft 10 clockwise for 90° and then extends 35 radially while from the other end of the slot 29 the wire 30 follows the periphery of the shaft 10 counterclockwise for 270° and then extends radially. The bridging member 31 consists of 40 two thin metal plates 32 each provided with a semi-cylindrical offset 33 and end contacts 34. The two plates 32 are interconnected as shown 45 in Fig. 5, thereby forming a central aperture through which the shaft 10 extends. The member 31 is at right angles to the slot 29 and the ends 35 of the wire 30 are bent parallel to the 50 axis of the shaft 10 and are affixed to the member 11 by any suitable means such, for example, as welds. This arrangement allows for slight overtravel of the shaft 10 in the same manner 55 as above described.

The arrangement herein disclosed is simple and inexpensive but effectively assures definite engagement of the movable contacts 22 and 23 with the stationary contacts 26 and 27. This assurance is obtained by having the extent of rotary travel of the shaft 10 slightly greater than is necessary normally to establish engagement between the movable and stationary contacts. By reason of this permissible overtravel, the movable contacts are definitely brought into engagement with the stationary contacts and are held in engagement by the tension exerted by the resilient members 14 and 15 in the first modification and 30 in the second modification.

I claim:

1. In a switch, a slotted rotatable shaft, a member rotatably mounted on said shaft, said member comprising a pair of interconnected metal plates having centrally arranged semi-cylindrical offsets defining an aperture receiving said shaft, a resilient element arranged in the shaft slot and having its ends attached to the ends of said member, a pair of stationary contacts on either side of each end of said member, and means to effect rotation of said shaft.

2. A switch according to claim 1 characterized by the shaft slot being at right angles to said member and said element being bent around said shaft in opposite directions from the ends of said slot over a portion of the shaft periphery.

3. In a switch, a slotted rotatable shaft, a member having an opening receiving said shaft, a resilient element arranged in the shaft slot and

having its ends attached to the ends of said member, a pair of stationary contacts on either side of each end of said member and means to effect rotation of said shaft.

4. A switch according to claim 3 characterized by the shaft slot being at right angles to said member and said element being bent around said shaft in opposite directions from the ends of said slot over a portion of the shaft periphery.

5. A switch comprising a slotted rotatable shaft having a central recess, a resilient element fitted into the shaft slot and having an enlarged portion fitting said recess, a member consisting of a pair of plates having opposed semi-cylindrical offsets forming an aperture rotatably receiving said shaft, said plates being connected at their ends to said element, a pair of stationary contacts at either side of each end of said member, and means to effect rotation of said shaft.

6. A switch according to claim 5 in which said resilient element comprises two thin plates having centrally opposite semi-cylindrical portions fitting said recess.
